CLAIM

The ornamental design for a display screen with graphical user interface, as shown and described.

DESCRIPTION

FIG. 1 is a front view of a display screen with user interface showing the new design;

showing the new design,
FIG. 2 is a second embodiment thereof; and,
FIG. 3 is a third embodiment thereof.
The broken line showing of the remainder of the graphical elements and the display screen in all views is for environmental purposes only and forms no part of the claimed design.

1 Claim, 3 Drawing Sheets
